UNITED STATES PATENT OFFICE.

WILLIAM H. RAY AND EDWARD CRAIG, OF ST. JOSEPH, MICHIGAN, ASSIGNORS TO SARANAC MACHINE CO., OF ST. JOSEPH, MICHIGAN, A CORPORATION OF MICHIGAN.

CORRUGATED-FASTENER MACHINE.

1,175,558.

Specification of Letters Patent.

Patented Mar. 14, 1916.

Application filed November 10, 1909. Serial No. 527,226.

To all whom it may concern:

Be it known that we, WILLIAM H. RAY and EDWARD CRAIG, citizens of the United States of America, and residents of St. Joseph, Berrien county, Michigan, have invented a certain new and useful Improvement in Corrugated-Fastener Machines, of which the following is a specification.

Our invention relates to machines for making and driving corrugated sheet metal fasteners. A machine of this kind is adapted to feed a sheet metal strip and cut and drive the same in suitable lengths. Each length is formed with corrugations which extend in the direction the fasteners are driven. Fasteners of this kind are now used extensively in the manufacture of articles requiring the fastening together of pieces of wood.

Our invention relates more particularly to machines which will drive a plurality of the said fasteners at the same time.

Objects of our invention are to provide an improved construction and arrangement whereby a plurality of fastener drivers are arranged tandem and in such manner that a bar, which is supported only at one end sustains the back thrust or strain incident to the driving of several fasteners at the same time; to provide simple and efficient means for adjusting the fastener drivers on the said bar, so as to change the position thereof; to provide a machine of this kind having the aforesaid features, and having an adjustable table for supporting the work below the said bar, and below the said fastener drivers; to provide an improved arrangement whereby one of the said fastener drivers is automatically rendered inoperative at certain times, so that the machine, after first driving a plurality of fasteners, may then drive a single fastener, or any number, according to requirements; and to provide certain details and combinations tending to increase the general efficiency and serviceability of a machine of this particular character.

To the foregoing and other useful ends,

our invention consists in matters hereafter set forth and claimed.

In the accompanying drawings, Figure 1 is a perspective of a corrugated sheet metal fastener driving machine embodying the principles of our invention. Fig. 2 is a perspective of the mechanism for operating the feed devices by which the strips or ribbons of metal are fed to the drivers. Fig. 3 is a view similar to Fig. 1, but showing the other side of the machine. Fig. 4 is a perspective of the star wheel by which the dog for one feed mechanism is automatically tripped in and out. Fig. 5 is an end elevation of the mechanism shown in Fig. 2, showing certain parts in section. Fig. 6 is a perspective of the feed dog shown in Fig. 5. Fig. 7 is a side elevation of the mechanism shown in Fig. 5. Fig. 8 is a section on line 8—8 in Fig. 5. Fig. 9 is a detail view of the device for varying the feed. Fig. 10 is a detail section, on an enlarged scale, of one of the cam connections for operating the drivers. Fig. 11 is a detail section on line 11—11 in Fig. 9. Figs. 12 to 18, inclusive, are detail views of the automatic clutch mechanism by which the machine is normally started and then automatically stopped after the driving of a set of fasteners.

As thus illustrated, and referring more particularly to Figs. 1 and 3, our invention comprises a base A and a standard or upright B upon which are mounted the various operative parts. At its upper end the said standard B is provided with bearings b and b' for the horizontal driving shaft C. This shaft has a clutch pulley D which is loose thereon, and which has clutch teeth d. The clutch member d' has a groove d² and a pinion d³, which is also loose on the shaft. The gear wheel d⁴ is fast on the said shaft C. There is a short countershaft d⁵ upon which are mounted the gear wheel d⁶ and the pinion d⁷. This shaft is mounted in bearings d⁸ and d⁹ formed at the top of the standard B. The pinion d³ engages the gear wheel d⁶ and the pinion d⁷ engages the gear wheel d⁴.

Thus the transmission of power is from the pinion d^2 to the gear wheel d^6 , through the shaft d^5 to the pinion d^7 , and from the latter to the gear wheel d^4 . The pulley D and the shaft C rotate in the same direction, but the wheel rotates faster than the shaft. The member d' has a spring pressed pin d^{10} that has a cam groove d^{11} adapted to lie in the groove d^2 . A lever d^{12} has a cam portion d^{13} and a locking portion d^{14} , the former portion adapted to lie in the groove d^2 . The said lever is operated by a rod d^{15} , which latter is in turn operated by a foot treadle d^{16} . When the said treadle is depressed the rod d^{15} moves upward and throws the cam portion d^{13} out of the groove d^2 . This releases the pin d^{10} and permits the latter to engage the clutch teeth d , whereby the shaft C is started rotating. The said shaft will rotate as long as the operator keeps the foot treadle depressed. If the said treadle is released, the portion d^{13} of the lever d^{12} engages the cam groove d^{11} in the pin d^{10} and causes the latter to disengage the teeth d , thus stopping the transmission of power to the driving shaft C. The foot treadle d^{16} can be locked in depressed position for a full rotation of the shaft, and then automatically released, by the rock shaft d^{17} which has a portion d^{18} adapted to rotate until its round outer side rests on top of the portion d^{14} , thus temporarily keeping the portion d^{13} from reentering the groove d^2 . This shaft d^{17} is provided with an arm d^{19} having a roll d^{20} engaged by a cam d^{21} on the shaft C. A handle d^{22} is connected with a spring d^{23} that keeps the roll d^{20} pressed against the cam d^{21} , and which causes the shaft d^{17} to rock and lock the lever d^{12} when the projection on the said cam passes out of engagement with the said roll. When the cam depresses the roll d^{20} , the shaft d^{17} is rocked to release the lever d^{12} , thus causing the machine to stop.

A heavy bar E is secured to the standard B and extends below and parallel with the shaft C. The fastener driving heads F and G, which may be of any suitable character, are mounted on this bar E. The two heads 50 are connected by a hand screw H, whereby the distance between the two heads may be varied at will by sliding the head G back and forth on the bar E. These heads have rigid upper portions f and g that support the shaft C, and that serve to connect the driving shaft to the heavy bar E. The said driving heads have feed mechanism f' and g' that are carried thereby and adapted to feed the strips of sheet metal from which the fasteners are made. These feed devices 55 can be of any suitable character, are provided with the usual or any suitable means, such as the little guides f³ and g³, for holding the sheet metal in position with its sharp

edge downward, and are operated by the ratchet mechanism I. This mechanism I is on a shaft i that extends parallel with the bar E and shaft C. Consequently, the strips of sheet metal are fed crosswise of the row of driving heads. The heads F and G are provided with bearings f² and g² in which the said shaft i is mounted. The rear end of the said shaft is supported in a thread bearing i' on the body B. The shaft i is geared to operate the feed mechanism f'; but the feed mechanism g' is operated by a sleeve i² on the shaft i. The shaft i is provided with a ratchet wheel i³, and the said sleeve with a similar ratchet wheel i⁴. The arm i⁵ is loose on the sleeve i², and has its upper portion pivotally connected with the end of the pitman i⁶, which latter is operated by a cam or eccentric on the shaft C. The pivot i⁷ that connects the arm i⁵ with the pitman i⁶ carries the dogs i⁸ and i⁹, which operate the wheels i³ and i⁴ respectively. The arm i⁵ has an extension i¹⁰ that carries a ratchet wheel i¹¹ and a star wheel i¹², which rotate together on a bolt or stud i¹³. The end of the pitman i⁶ carries a dog i¹⁴ that operates the ratchet wheel i¹¹. When a point or tooth of the star wheel i¹² engages the top of the dog i⁹ the latter is held out of engagement with the ratchet wheel i⁴. At one stroke both ratchet wheels i³ and i⁴ are rotated, but at the next stroke of the pitman i⁶ the ratchet wheel i⁴ does not operate, as the wheel i¹³ has rotated and lifted the dog i⁹ out of engagement with the wheel i⁴. Thus at every other stroke only one fastener is driven, as only the feed mechanism f' is operated. The arm i⁵ can be reversed or turned around on the sleeve i², so that the star wheel i¹² will then engage the dog i⁸. Thus either feed mechanism can be rendered inoperative and thus one of the drivers will drive a fastener only every other stroke of the said feed mechanism. This enables the operator to drive a plurality of fasteners, and to then drive one. This is of advantage in certain kinds of work. The feed can be varied at will by means of a handle i¹⁵, which handle is rigid with a pair of disks i¹⁶ and i¹⁷, which are adapted to turn on the shaft i and the sleeve i². These disks have cam depressions i¹⁸ in which the dogs i⁸ and i⁹ travel back and forth. By means of a series of holes i¹⁹ in the disks i¹⁶ and a spring pressed pin i²⁰ the said disks can be held in various positions. For example, the disks can be turned one way until the dogs i⁸ and i⁹, on their forward stroke, do not enter the depressions i¹⁸ as soon as they did before, and with the result that the feed is shortened. The dogs i⁸ and i⁹ after the end of the dogs enter the depressions i¹⁸, and if this is varied the feed

is varied accordingly. The disks can be rotated to entirely throw the dogs out of operation, by adjusting them so that the hole i^{21} is engaged by the pin i^{20} . Another hole i^{22} , when engaged by said pin, causes the dogs to disengage sooner from the ratchet wheels, thus varying the feed in another way.

The sleeve i^2 may be provided with a spline or feather to permit the gear which 10 operates the feed mechanism to slide thereon when the portion of the head G is changed by the hand wheel H.

The shaft C is provided with cams J and K which operate the drivers of the heads F and G. In Fig. 10 the cam J is shown connected for operating the driver f^3 of the head F. These cams are circular and have eccentric grooves, such as the groove j , for 15 engaging rolls or studs on the upper ends of the drivers. For example, the roll or stud f^4 on the driver f^3 engages the groove j , whereby the said driver is actuated by the 20 rotation of the shaft C.

The table L is adapted to support the 25 work below the driving heads F and G, and is movable up and down by means of the hand screw l. Thus the work can be raised or lowered at will. The screw l sustains the thrust of the fastener drivers. The driving 30 heads are arranged tandem, one in front of the other, and the space below is accessible from the front or either side of the table.

What we claim as our invention is:

1. In a machine for driving corrugated 35 sheet metal fasteners, a plurality of driver heads arranged in a row, a feed shaft, a feed sleeve on said shaft, a feed mechanism for one head operated by said shaft, a feed mechanism for the other head operated by 40 said sleeve, ratchet devices for operating said shaft and sleeve, and devices for operating the operative parts of said heads, the said shaft and row of heads being parallel, together with a drive shaft for operating 45 said heads and feed shaft, said ratchet devices having a single pitman extending thereto from said drive shaft.

2. In a machine for driving corrugated 50 sheet metal fasteners, a plurality of driver heads, a feed mechanism for each head, means for actuating said feed mechanisms, and skipping means associated with said actuating means for causing one feed mechanism to operate only once for every two operations of the other feed mechanism.

3. In a machine for driving corrugated 55 sheet metal fasteners, a fastener driver head, a feed mechanism therefor, means for operating the operative parts of said head, means whereby said feed mechanism operates only once for every two operations of said head, another driver head, and a feed mechanism for said last-mentioned head, operative for each actuation thereof.

4. In a machine for driving corrugated 65 sheet metal fasteners, ratchet wheels, a dog for each wheel, means for actuating said dogs, and means including a ratchet-operated wheel for causing one dog to operate only once for every plurality of operations 70 of the other dog.

5. In a fastener driving machine, a head having a driver, a shaft, a cam on said shaft, provided with a groove in the side thereof, means on said driver for engaging 75 said groove, a support for said head, and means for engaging said shaft close to the cam, fixed on said head, to prevent the shaft and support from separating during 80 the driving operation.

6. In a fastener driving machine, a head having a driver, a shaft, a cam on said shaft, provided with a groove in the side thereof, means on said driver for engaging 85 said groove, a support for said head, and means for engaging said shaft close to the cam, fixed on said head, to prevent the shaft and support from separating during the driving operation, together with means for adjusting said head along said support and 90 shaft.

7. In a fastener driving machine, a head having a driver, a shaft, a cam on said shaft, provided with a groove in the side thereof, means on said driver for engaging 95 said groove, a support for said head, means for engaging said shaft close to the cam, fixed on said head, to prevent the shaft and support from separating during the driving operation, together with another drive 100 head and cam, and means for varying the distance between said heads.

8. In a fastener driving machine, a horizontal bar, a shaft parallel with said bar, a plurality of driver heads on said bar, provided with means for preventing separation of the bar and shaft, cams on said shaft, means on said heads for engaging said cams, and means for varying the distance between 105 said heads.

9. In a fastener driving machine, a horizontal bar, a shaft parallel with said bar, a plurality of driver heads on said bar, provided with means for preventing separation of the bar and shaft, cams on said shaft, 115 means on said heads for engaging said cams, and means for varying the distance between said heads, comprising a screw connecting one head with the other, disposed at one side of said bar.

10. In a fastener driving machine, a horizontal bar, a shaft parallel with said bar, a plurality of driver heads on said bar, provided with means for preventing separation of the bar and shaft, cams on said 125 shaft, means on said heads for engaging said cams, and means for varying the distance between said heads, the head at the

outer end of said bar having a fixed position thereon.

11. In a fastener driving machine, a horizontal bar, a shaft parallel with said bar, a plurality of driver heads on said bar, provided with means for preventing separation of the bar and shaft, cams on said shaft, means on said heads for engaging said cams, and means for varying the distance between said heads, comprising a screw connecting one head with the other,

disposed at one side of said bar, the head at the outer end of said bar having a fixed position thereon.

Signed by us at St. Joseph, Michigan, 15 this 4th day of November, 1909.

WILLIAM H. RAY.
EDWARD CRAIG.
